UNITED STATES PATENT OFFICE.

ROBERT S. BLAIR, OF STAMFORD, CONNECTICUT.

PROJECTION OF BULLETS AND OTHER PROJECTILES.

Application filed April 26, 1923, Serial No. 634,682. Renewed August 11, 1927.

This invention relates to the projection of bullets and projectiles of like character. One of the objects thereof is to provide a practical art whereby the precision of travel of a projectile through the air is substantially enhanced. Another object is to provide an art of the above character whereby forces tending to detract from the accuracy of projection of a bullet or the like are effectively counteracted. Another object is to provide means dependable in action and capable of maintaining a high degree of precision in the firing of projectiles. Other objects will be in part obvious or in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawing in which are shown one or more of the various possible embodiments of the mechanical features of this invention,

Figure 1 shows diagrammatically in side elevation a path of travel of a projectile;

Figure 2 is a view similar to Fig. 1 with certain additional features;

Figure 3 is a vertical, sectional elevation of the end of a gun barrel showing a projectile;

Figure 4 is a sectional plan view of the gun barrel shown in Fig. 3;

Figure 5 is a plan view of a path of a projectile;

Figure 6 is a side elevation of Fig. 5;

Figure 7 is an end view of the gun barrel shown in Figs. 3 and 4, together with a diagrammatic representation of certain tendencies of movement of a moving projectile;

Figure 8 is a view similar to Fig. 7 showing a modification;

Figure 8^a is a view looking toward an approaching projectile showing the projectile in two different positions; and

Figure 9 is a plan view of the path of a projectile.

Similar reference characters refer to similar parts throughout the several views of the drawing.

Referring now to the drawing in detail, there is shown in Fig. 1 the normal path

of a projectile fired, for example, from a point 10 at an objective 11. A projectile moving through the air acted upon the impulse imparted to it at firing and by gravity normally follows a path tracing substantially the curve of a parabola. As shown in Fig. 1, however, the curve is substantially a straight line for a substantial distance from the point of projection until the projectile reaches a point such as 12, for example, when the curve starts to drop off more rapidly. If, for example, the projectile is fired substantially horizontally at an objective point 11, its path will normally be that indicated by the full line in Fig. 1 instead of the desired straight path indicated by the dotted line, and the projectile will fall below the mark.

Referring now to Fig. 3, there is shown the end portion 13 of the barrel of a rifle or gun or the like and a projectile 14. When a projectile is fired from a gun the impulse given the projectile is the result of the force exerted by the rapidly expanding gases generated by the ignition of the explosive charge. These gases expanding against the rear face of the projectile force their way in between the sides of the projectile and the walls of the bore of the gun with the result that the projectile is accompanied throughout the length of its travel through the gun barrel by a layer of gases between its sides and the walls of the gun barrel, which gases exert a pressure from all sides of the projectile transversely of its axis. In Figs. 3 and 4 the gun barrel 13 is shown as having the upper portion of its extreme end cut away, or, which amounts to the same thing, as having its lower portion extended to form a projection 16. As the rear end of the projectile 14 passes the end 15, the downward effect of the above-mentioned pressure exerted by the gases between the walls of the gun barrel and the projectile is suddenly released while the upward pressure caused by the gases between the projectile and the portion 16 of the barrel remains effective. The effect of this is that a force is exerted upon the rear end of the projectile transversely to its axis, which force tends to move the rear end of the projectile upwardly.

The bore of a gun is rifled to give the projectile discharged therefrom a rapid rotating movement about its longitudinal axis, and

a body rapidly rotating about an axis acts as a gyroscope. The end of the axis of rotation of a rotating gyroscope always tends to move at right angles to any force impressed upon it, which effect is known as the gyroscopic reaction. Thus, if, for example, the projectile 14 is rotating about its axis in the direction indicated by the arrows in Figs. 3 and 4, the above-mentioned force exerted upwardly upon its rear portion as it leaves the gun barrel results in a lateral turning of the axis of the projectile to a position such as that shown in Fig. 4 which is a plan view. The projectile 14, therefore, is projected from the gun traveling along the line of projection 17 rotating about its longitudinal axis and with that axis turned laterally at an angle with respect to the line of travel. It is to be understood that the above-described method and apparatus for bringing about this turning of the axis of the projectile is illustrative only and that other means may be employed to bring about a similar result.

As the projectile 14 moves through the air with its axis in a position as indicated in Fig. 4, its side surface 14^a is exposed to wind pressure while its opposite surface 14^b is substantially free from such pressure. A force is thereby exerted upon the surface 14^a tending to thrust the forward end of the projectile in a direction indicated substantially by the arrow 18. Since, as before explained, the end of the axis of a rotating gyroscope always tends to move at right angles to any force impressed upon it, the result of the force indicated by the arrow 18 will be a movement of the forward end of the projectile upwardly or a tipping upwardly of the projectile with respect to its line of travel. The projectile is traveling rapidly through the air and this gyroscopic reaction to the air pressure 18 takes effect along its path of travel, preferably resulting in an upward tilt of the projectile with respect to its line of travel substantially when it reaches the vicinity of the point 12 indicated in Fig. 2, where it tends to drop substantially due to the effect of gravity. The axis of the projectile being thus inclined upwardly, the pressure of the air from beneath exerts a force thereon which tends to cause the projectile to volplane or drift upwardly along a path such as indicated by the line 25, for example. Thus, the effect of gravity tending to cause the projectile to follow a path such as 26 is effectively counteracted or offset so that the projectile continues in a substantially straight line with respect to the horizontal and reaches the objective in a lateral plane substantially coincident with the objective point 11. This turning of the axis of the projectile and the effects thereof may be better realized by reference to Fig. 6 which is a view similar

to Fig. 2 showing diagrammatically the positions of the projectile with respect to its line of travel when adjacent the end of the gun barrel and also when in the vicinity of the point 12.

As the projectile travels through the air with its axis at an angle with respect to the line of travel as indicated in Fig. 4, the wind pressure thereon causes a lateral drift, the projectile tending to follow a path such as that indicated by the solid line in the plan view shown in Fig. 5. The projectile thus strikes the objective at one side of the objective point 11 although, as above described, the upward drift or volplaning as it approaches the objective causes it to strike at substantially the desired elevation, as is shown in the side view in Fig. 6. Referring now to Fig. 7, there is shown an end elevation of the gun barrel shown in Figs. 3 and 4. The arrow 19 represents the direction with respect to the line of the gun barrel in which the projectile tends to drift during the first part of its travel or while its axis is turned, as is shown in Fig. 4. The arrow 20 indicates the direction in which the projectile tends to drift through the latter part of its travel, that is, after it has reached the vicinity of the point 12, and its axis is turned as is indicated at 12 in Fig. 6. In Fig. 8 there is shown an end view of a gun barrel shaped similarly to that shown in the preceding figures except that its end is cut away on a line substantially 45° with respect to the horizontal instead of being cut away along a horizontal line. As the projectile is discharged from the end of the barrel shown in Fig. 8, the effect is similar to that above described with regard to Figs. 3 and 4, that is, its rear portion is given a thrust which tends to turn the axis of the projectile at an angle with respect to its line of travel, but this thrust is in a direction substantially as indicated by the arrow 21 in Fig. 8 instead of in a vertical direction as in the preceding case. The gyroscopic reaction of the projectile to this thrust causes the rear end thereof to move in a direction indicated by the arrow 22 and thus its axis is turned at an angle to its line of travel and in a plane angularly disposed with respect to both the horizontal and vertical. That is, the forward end of the projectile is inclined upwardly and also to one side with respect to its line of travel. The arrow 23 of Fig. 8 indicates the direction with respect to the line of travel in which the projectile tends to drift due to wind pressure thereon while its axis is so inclined. When the projectile reaches the vicinity of the point 12 its gyroscopic reaction to this wind pressure, as before described, will have resulted in a movement of the forward end thereof at right angles to the wind pressure indicated by the arrow 23, so that the axis of the projectile

is now inclined with respect to its line of travel similarly to its inclination upon leaving the gun barrel but at the other side of the vertical. These two inclinations may be

better realized by reference to Fig. 8^a where in 14^a is a view looking toward the approaching projectile during the first part of its travel, and 14^b is a similar view of the projectile after it has reached the vicinity of the point 12. In this latter position the direction in which the projectile tends to drift is substantially indicated by the arrow 24 in Fig. 8. Thus the tendency of the projectile to drift from a straight path is made up sub-

stantially of the summation of the tendency to drift in the two directions indicated by the arrows 23 and 24. The lateral components of the two drifts are in opposite directions; the drift during the first part 20 of the projectile's travel being to the left, and the drift during the latter part of its travel being toward the right, so that a plan view of the path of the projectile is substantially as indicated by the full line in Fig. 9.

25 Thus the projectile drifts toward one side and then back again so that it strikes the objective in a vertical plane substantially coincident with the objective point 11. At the same time there is a resultant vertical 30 component of the two drifts which tends to move the projectile in an upward direction and thereby counteracts or offsets the effect of gravity tending to cause the projectile to fall as above described with regard to Fig. 35 2. Thus the projectile strikes the objective at substantially the desired point with respect to both the vertical and the horizontal.

From the above it will be seen that there is herein provided an art and means for carrying on the same which embody the features of this invention and attain the objects thereof.

It may be noted at this point that the proportions and angles as herein illustratively shown are much exaggerated in order to bring out the principles involved, and that the method shown of exerting a tilting force on the projectile as it leaves the gun is merely an example having in itself nothing to do with the dominant features of this invention. The tilting means should merely exert such force on the projectile that when it starts its flight after it leaves the gun, it will be, in the first case hereinbefore described, laterally inclined with respect to its direction of flight at such an angle that the air resistance combined with the gyroscopic action will tend to tilt the front end upwardly. In like manner, in the second case hereinbefore described, the projectile should start its flight outside the gun inclined laterally and upwardly, with the lateral inclination such with respect to the rifling or rotation of the projectile that the air resistance combined with gyroscopic ac-

tion will tend at first to decrease the lateral inclination and increase the upward inclination.

As various possible embodiments may be made of the mechanical features of the above invention and as the art herein described might be varied in various parts, all without departing from the scope of the invention, it is to be understood that all matter herein set forth or shown in the accompanying drawings is to be interpreted as illustrative and not in a limiting sense.

I claim as my invention:

1. The herein described art which consists in turning the axis of a rotating projectile 80 at an angle with respect to its direction of flight to offset the effect of gravity tending to cause the projectile to drop.

2. The herein described art which consists in utilizing the air pressure upon an elongated rotating projectile in its movement through the air to exert a lifting effect upon the projectile and offset the effect of gravity thereon.

3. The herein described art which consists 90 in turning the axis of a rotating projectile at an angle with respect to its direction of flight to expose the side portions of the projectile to air pressure to exert a lifting effect thereon and offset the tendency thereof to drop due to gravity.

4. The herein described art which consists in turning the axis of a rotating projectile at an angle with respect to its direction of travel to subject the projectile to air pressure acting at an angle to its axis and thereby exerting a lifting effect thereon.

5. The herein described art which consists in turning the axis of a rotating projectile at an angle with respect to its direction of flight whereby the projectile is subjected to air pressure transversely to its axis effecting a gyroscopic reaction of the projectile tending to again turn its axis with respect to its direction of flight.

6. The herein described art which consists in turning the axis of a rotating projectile with respect to its direction of flight to tend to cause a lateral drift of the projectile first in one direction and then in the opposite direction.

7. The herein described art which consists in turning the axis of a rotating projectile at an angle with respect to its line of movement through the air to tend to cause a drift 120 of said projectile in a direction substantially opposite to the direction in which the projectile tends to move due to gravity.

8. The herein described art which consists in subjecting a rotating projectile to a 125 thrust substantially transversely to its axis as it leaves the muzzle of a gun to tend to turn the axis of the projectile at an angle to its direction of flight and effect a drift pressure on the projectile.

9. In apparatus of the general nature of that herein described, in combination, means for discharging an elongated rotating projectile through the air, and means associated with said discharge means adapted to turn the axis of rotation of said projectile at an angle with respect to its line of flight.

10. In apparatus of the general nature of that herein described, in combination, a gun barrel for discharging a rotating projectile, and means adapted to exert a thrust upon said projectile transversely to its axis of rotation as it leaves the end of said gun barrel.

11. In apparatus of the general nature of that herein described, in combination, a gun barrel for discharging a rotating projectile, and means associated with the end portion thereof adapted to effect a thrust upon the projectile transversely to its axis of rotation as it passes therefrom.

12. The herein described art which consists in giving a rotating projectile an initial impulse at the muzzle of the gun which results in an angular displacement of the axis of the projectile relative to its line of flight thereby causing a drift pressure which due to the gyroscopic effect of the projectile again displaces the axis of the projectile relative to its line of flight resulting in a drift pressure which tends to compensate for the effect of gravitational forces on the projectile.

13. The herein described art which consists in firing a rotating projectile through the air with its axis of rotation inclined at such an angle with respect to its direction of flight that the air pressure upon the rotating projectile exerts a lifting effect thereon tending to offset the effect of gravitational forces.

14. The herein described art which consists in firing a rotating projectile through the air with its axis of rotation inclined at such an angle to its direction of flight that the air pressure upon the rotating projectile tends to cause a lateral drift thereof.

15. The herein described art which consists in firing a rotating projectile through the air with its axis of rotation inclined at such an angle to its direction of flight that the air pressure upon the rotating projectile tends to cause a lateral drift thereof in one direction throughout a portion of its flight and then, due to the gyroscopic effect of the projectile, causes the axis of the projectile to turn at another angle with respect to its direction of flight so that, during another portion of its travel, the air pressure thereon tends to cause a lateral drift in a direction opposite to said first drift.

16. The herein described art which consists in firing a rotating projectile through the air with its longitudinal axis about

which it rotates inclined with respect to the direction of flight of the projectile to effect a drift pressure thereon.

17. The herein described art which consists in firing an elongated projectile through the air rotating about its longitudinal axis and with its nose inclined upwardly with respect to its line of flight so that the air pressure exerts a lifting effect upon the projectile to counteract gravitational forces acting thereon.

18. The herein described art which consists in firing a rotating projectile through the air with its axis of rotation inclined at such an angle to its direction of flight that the air pressure upon the rotating projectile tends to cause a combined lateral drift and upward drift.

19. The herein described art which consists in firing a rotating projectile through the air with its axis of rotation inclined at such an angle to its direction of flight that the air pressure upon the rotating projectile tends to cause a combined lateral drift and upward drift throughout a portion of its flight and then, due to the gyroscopic effect of the projectile, causes the axis of the projectile to turn at another angle with respect to the direction of flight so that, during another portion of the projectile's flight, the wind pressure thereon tends to cause a lateral drift in a direction opposite to said first lateral drift to counteract said first lateral drift and an upward drift to counteract gravitational forces.

20. The herein described art which consists in firing a rotating projectile through the air with its axis of rotation inclined at such an angle to its direction of flight that the air pressure upon the rotating projectile tends to cause a lateral drift throughout a portion of its flight and then, due to the gyroscopic effect of the projectile, causes the axis of the projectile to turn at another angle with respect to the direction of flight so that, during another portion of the projectile's flight, the wind pressure thereon tends to cause another lateral drift to counteract said first lateral drift and an upward drift to counteract gravitational forces.

21. The herein described art which consists in firing a rotating projectile through the air with its axis of rotation inclined at an angle relative to its line of flight thereby causing a drift pressure which, due to the gyroscopic effect of the projectile, displaces the axis of the projectile to another position relative to its line of flight resulting in a drift pressure which tends to compensate for the effect of gravitational forces.

In testimony whereof, I have signed my name to this specification this 20th day of April, 1923.

ROBERT S. BLAIR.
